(57) CLAIM

The ornamental design for a single-sole shoe with blue outpatch sole, as shown and described.

DESCRIPTION

FIG. 1 is a perspective view of an embodiment of our new design of a single-sole shoe with blue outpatch sole, where the blue portions are indicated using the USPTO convention of horizontal lines for blue;

FIG. 2 is a first side view of the design of FIG. 1;

FIG. 3 is a second side view of the design of FIG. 1;

FIG. 4 is a top view of the design of FIG. 1;

FIG. 5 is a bottom view of the design of FIG. 1;

FIG. 6 is a front view of the design of FIG. 1; and,

FIG. 7 is a back view of the design of FIG. 1.

The broken lines illustrating the upper rim elastic, the half moon patch, the groove in the outsole, and the heel stripe in the above described Figures are for illustrative purposes only and form no part of the claimed design.
